UNITED STATES PATENT OFFICE.

EMIL DEISTER, OF FORT WAYNE, INDIANA, ASSIGNOR TO THE DEISTER CONCENTRATOR COMPANY, A CORPORATION OF INDIANA.

ORE-CONCENTRATOR.

No. 921,089.

Specification of Letters Patent. Patented May 11, 1909.

Application filed August 17, 1905. Serial No. 274,515.

To all whom it may concern:

Be it known that I, EMIL DEISTER, a citizen of the United States of America, and resident of Fort Wayne, in the county of Allen and State of Indiana, have invented certain new and useful Improvements in Ore-Concentrators, of which the following is a specification.

This invention relates to improvements in concentrators for treating ore pulp, and the object thereof is to provide a machine in which the transient body of pulp will become enriched by an accumulation of values, and from which the concentrates product, in a clean state, will become extracted; and a further object is to so construct the machine as to avoid serious loss of values or an un-clean concentrates product which ordinarily occurs because of variations in richness of the pulp as well as irregularity in supplying pulp to the machine. These objects are accomplished by the construction illustrated in the accompanying drawings, in which:

Figure 1. is a plan view of the machine, 25 with parts thereof cut away; Fig. 2. is a vertical sectional view on the line x—x of Fig. 1; Fig. 3. is a plan view of one of the shoals; Fig. 4. is a sectional view of one of the shoals and a portion of the concentrating-pan; 30 Fig. 5. is a detail view in perspective, showing one of the series of shoals which form a part of the machine; Fig. 6. is a detail sectional view of a portion of the machine showing one of the struts which connect the concentrating-pan and frame for holding the former in central relation with the latter.

Similar numerals of reference indicate corresponding parts throughout the several views, and referring now to the same—

1 is a supporting frame having bearings 2 in which is mounted a driving-shaft 3.

4 is a concentrating-pan having the form of a ring and with its outer and inner margins upturned, the latter forming an annular dam 5. The outer portion of the pan is flat and affords a continuous level annular path 6; and the inner portion 7 of the pan slopes downwardly from the path 6 toward the dam 5, and has thereon a uniform series of helical 45 riffles 8, each of which ranges in its course gradually outward from the gutter 9 and terminates at the inner margin of the path 6. The gutter 9 is annular, and a series of openings 10 lead therefrom through the pan, the 50 openings serving for the discharge of tailings.

A funnel 11 is mounted centrally in connection with the frame 1 beneath the concentrating-pan, and the pan has supported relation with the frame by means of a series of swinging stanchions 12. The concentrating-pan is held in central relation with the frame 1 and in proper position upon the stanchions 12 by means of radial struts 13, each of which has a hooked connection at its inner end with the corresponding brace 14, which is fixed to the underside of the pan, and has at its outer end a yielding connection with the frame 1. The yielding connection is formed by placing the sleeve 15 and nuts 16 upon the end of the strut which extends through the frame and with a leather washer 17 interposed between the sleeve and nuts.

Upon the ends of the driving-shaft 3 are mounted oppositely disposed eccentrics 18, each having in connection therewith a driving rod 19 which extends loosely through a corresponding bracket 20, the latter being fixed to the underside of the pan at a point diametrically opposite the other bracket. Each of said driving rods has mounted thereon a driving head consisting of a rubber buffer 21 which impinges the side of the adjacent bracket 20, and upon the opposite side of said bracket a compression spring 22 is arranged in connection with an adjusting collar 23. Each buffer is interposed between the corresponding bracket and a collar 24 which is rigidly fixed upon the driving rod. The parts of the respective driving-heads are arranged relatively opposite so that when the driving-rods are actuated a differentially oscillated motion will be imparted to the pan, the differential tendency of which is such as to cause the pulp to move in the direction indicated by the arrow. 95 Tight and loose pulleys 25 are mounted upon the shaft 3 for the purpose of connecting the same with a driving-belt.

Upon the level path 6, adjacent the rifled inner portion of the pan, is arranged an annular series of shoals 26 which constitutes a particular feature of this invention. Each shoal is located preferably at the outer terminal of a riffle 8, and the upper surface thereof gradually ascends from the surface of the path 6 toward its head 27. The sides of the shoal gradually narrow toward its head, and the upper or concentrating surface 28 of the shoal becomes narrow at its upper portion and leads up to the throat 29 which 110

communicates with the concentrates discharge-opening 30, the latter connecting with the discharge-spout 31. Upon either side of the throat 29 is a miniature plateau 32, each of which extends to the corresponding edge of the shoal, and has a gradually rounded inner edge 33. Upon the concentrating surface of the shoal is arranged a series of convergently disposed riffles 34, the 10 uppermost pair of which extends between the plateau toward the entrance of the throat 29. The head 27 of the shoal is hollow and has an elongated opening 35 at its top, and also discharge ports 36 which lead 15 respectively out onto the corresponding plateaus 32. The height of the shoal at the throat is approximately in line with the level of water in the pan as established by the height of the dam.

20 A series of pipes 37, having water taps 38 at their outer ends lead from a central fountain 39 which is supplied with dressing water through a pipe 40, and each of the pipes 37 is adapted to discharge dressing 25 water into the head of the corresponding shoal, the quantity of water thus supplied to the shoals is regulated by manipulating the taps 38. It is desirable that the ore pulp be fed to the pan uniformly around its outer 30 margin, and to effect this, an annular feed trough 41, having numerous openings 42 in its bottom, is attached to the pan slightly above the water level therein, and a series of radial feed spouts 43 lead from a central hopper 44 into the feed trough. The feed spouts and hopper are rigidly connected together and are supported by braces 45, the lower ends of which rest in the funnel 11, and the fountain 39 is supported by attachment to 35 the underside of the hopper 44.

40 In the operation of this invention, the pan is set in oscillating motion by means of the driving mechanism, and ore pulp is then conveyed to the hopper through a supply pipe 46 from whence it gravitates through the feed spouts and feed trough onto the concentrating-path 6 evenly at the outer margin thereof. The ore tends to settle upon the concentrating surface of the pan, 45 and the overlying portion thereof will work inward over the riffles toward the gutter 9, and because of the helical riffles, and the differential motion of the pan, the underlying portion of the ore will be continually carried 50 outward onto the path 6. It will therefore appear that the mineral values of the ore, being heavier than the matrix and therefore lowermost in the pan, will tend to accumulate more or less upon the path 6; and the gangue or overlying portion of the pulp will continually move to the gutter 9 and be discharged through the openings 10. It is the intention that the level of water in the pan shall be above that of the settled pulp therein, and to effect this condition more or less

of the openings 10 may be plugged so that water from the pan will continuously overflow the dam 5, but a sufficient number of the openings 10 are left open to insure the passage of coarse tailings so that no detrimental accumulation occurs. The tailings discharged through the openings 10, and the water passing over the dam 5 fall into the funnel 11 and pass therefrom through its lower end. As the enriched body of pulp 70 upon the path 6 moves around the pan, it enters the shoals, and because of the projection of the latter and the convergence of the riffles thereon, the pulp becomes congested more or less toward the center thereof, and is also raised, accordingly above the general ore level in the pan. The overlying portion of the ore matter on the shoals tends to work laterally outward, and the underlying portion thereof is influenced inwardly 80 by the riffles as it passes toward the throats. The overlying portion of the pulp upon the shoals carries more or less gangue which is gently washed away because of its movement in the water which lies above the general ore level in the pan; and as the congested concentrates pass between the plateaus, the mass of concentrates in the throat of each shoal becomes washed clean of its overlying portion by the dressing water 90 which issues from the ports 36, and the concentrates thus cleansed pass into the openings 30, and are discharged from the spouts 31. The dressing water passes from the ports and spreads out upon the plateaus and 100 floats the overlying ore-matter over the edges of the shoals back again into the pan.

Having described my invention what I claim as new and desire to secure by Letters Patent, is:

1. In an ore concentrator, a differentially actuated pan adapted to maintain a water level therein slightly above the general level of settled ore-matter in the pan; a gradually ascending shoal projecting from the concentrating surface of the pan and having a discharge-opening, and throat leading to the opening from the inclined concentrating surface of the shoal, and having also ports leading from the head of the shoal, adapted to discharge dressing water adjacent the respective sides of the throat thereof. 110

2. In an ore concentrator, a differentially actuated concentrating pan having a gradually ascending shoal resting upon its concentrating surface, the shoal having a discharge-opening near its head, and throat leading to the opening from the inclined concentrating surface of the shoal, the throat being comparatively narrower than said inclined surface. 120

3. In an ore concentrator, a differentially actuated concentrating-pan; and a gradually ascending shoal resting upon the concentrating-surface of the pan, and having a dis- 130

- charge-opening near its head, and throat leading to its opening from the inclined concentrating surface thereof; and having also ports leading from its head, adapted to discharge dressing water to said shoal adjacent the respective sides of the throat thereof.
4. In an ore concentrator, a differentially actuated pan having a concentrates path and an inclined portion with riffles thereon adapted to direct underlying ore-matter to said path; a dam in connection with the pan at its tailings discharge edge, the pan having a series of openings leading through its bottom adjacent the dam; and one or more shoals located on the concentrates path of the pan and projecting gradually upward therefrom and each having a discharge opening for concentrates, the dam being adapted to maintain the water level in the pan approximately up to the openings in the shoals.
5. In an ore concentrator, a differentially actuated concentrating-pan; a gradually ascending shoal projecting from the concentrates path of the pan, and having a discharge-opening near its head, and throat leading to the opening from the inclined concentrating surface of the shoal, and having also convergently disposed riffles upon its concentrating surface leading toward its throat.
6. In an ore concentrator, a differentially actuated concentrating-pan; a gradually ascending shoal adapted to receive ore matter from the concentrating surface of the pan, and having a discharge-opening near its upper end, and throat leading to the opening from its inclined concentrating surface, the throat being comparatively narrower than the latter surface; and means for discharging dressing water upon said shoal adjacent its throat.
7. In an ore concentrator, a differentially actuated concentrating-pan; and a gradually ascending-shoal adapted to receive ore matter from the concentrating surface of the pan, and having plateaus near its discharge-end, and a throat intervening between the plateaus, and ports adapted to discharge dressing water upon the plateaus, and having also a discharge-opening, the said throat leading to said opening from the inclined concentrating surface of the shoal.
8. In an ore concentrator, a differentially actuated concentrating-pan; a gradually ascending shoal adapted to receive ore-matter from the concentrating surface of the pan, and having plateaus near its discharge-end, and a throat intervening between the plateaus; and having also ports leading to the plateaus respectively, and a discharge opening at the end of the throat; and riffles arranged upon the concentrating surface of the shoal which lead toward the throat thereof.
9. In an ore concentrator, a differentially actuated concentrating-pan having one or more gradually ascending shoals adapted to receive ore-matter from the concentrating surface thereof, and each shoal having a concentrates discharge-opening near its upper end, and throat leading to the opening from the inclined concentrating surface of the shoal, the pan being adapted to maintain a water level therein approximately in line with the throats of the shoals.
10. In an ore concentrator, a differentially actuated concentrating pan having one or more gradually ascending shoals adapted to receive ore-matter from the concentrating surface thereof, and each having a concentrates discharge-opening near its upper end and throat leading to the opening from the inclined concentrating surface of the shoal, the throat being comparatively narrower than the latter surface, and means for applying dressing water to the shoals to float the overlying ore matter upon the shoals back again into the pan.

In testimony whereof I affix my signature, in presence of two witnesses.
